MINE CAR

Henry P. Field, Berwick, Pa., assignor to American Car and Foundry Company, New York, N. Y., a corporation of New Jersey

Application October 20, 1931, Serial No. 569,937

25 Claims. (Cl. 105—364)

This invention relates to mine cars and with regard to certain more specific features thereof to mine cars constructed in large part of sheet and rolled metal and adapted when assembled to be supported on axles.

The invention has for one of its objects to provide a strong but relatively light weight car having exceptional stability and large capacity.

Another object of the invention is to provide a simple and inexpensive car construction which may be quickly and conveniently assembled complete with axles and wheels.

A further object is to provide a particularly durable car offering a high resistance to the severe strains associated with the operation of mine cars.

Other objects will appear from the following description of the construction and operation of this improved mine car.

The invention accordingly consists in the various features of construction, combinations of elements and arrangements of parts which are exemplified by the construction hereinafter set forth and the scope of the application of which will be indicated in the appended claims.

Referring now to the drawings, wherein is shown one of various possible embodiments of the invention:—

Figs. 1 and 2 conjointly represent a mine car in longitudinal section; in Fig. 1 the section is taken along the median line and in Fig. 2 along the line 2—2 of Fig. 3;

Fig. 3 is a top plan view of the construction shown in Fig. 2;

Fig. 4 is a view in cross section taken on the line 4—4 of Fig. 3; and

Fig. 5 is a view in cross section taken on the line 5—5 of Fig. 3.

Referring now more particularly to the drawings, supporting elements 10 and 11 are provided in the form of spaced parallel longitudinal sills. Preferably these are rolled metal bulb-angles comprising webs 12 developing at their upper extremities into beads or heads 13. As these bulb-angles are arranged in the present construction lower horizontal flanges 14 extend inwardly toward the center line of the body.

Secured to the flanges 14 as by riveting or welding are bail-shaped members 15 having horizontal flanges 16, supported on the sill flanges 14, upright portions 17 and horizontal flooring portions 18. Preferably three of these members 15 are employed as shown in Figs. 1 and 2 of the drawings, there being one section between the car axles and one between each car axle and its corresponding end. These members constitute what

is termed herein the central flooring which is completed by axle hoods or shrouds 19 riveted to the horizontal flooring portions 18 and also to the uprights 17, of the floor members 15.

To the outer faces of the web 12 of the sills 10 and 11 the upright flange of sheet metal side floor sheet members 20 are attached as by rivets 21. The upright flange of these members depends from the sills to the angle point 22 where a horizontal floor 23 extends outwardly thereby providing what are termed herein side floor portions. In the present form of the invention there are three of the floor sheet members 20 on each side of the car, these being spaced apart at their ends to accommodate the car wheels.

Spaced outwardly from the supporting sills 10 and 11 are sheet metal side walls 24. These walls extend substantially higher than the plane of the top of the sills and have rolled-over edges 25 for strengthening purposes. The side walls also extend lower than the plane of the bottom of the sills, their lowermost extremities 26 having turned-in flanges 27 which are overlapped by the horizontal web portion or side flooring 23 and secured in overlapped relation.

End walls 28 of similar construction to the side walls and located in substantially the same horizontal plane are joined to the side walls by suitable angle irons 30 at the corners. The end walls 28 are also joined to the sills 10 and 11 by angle irons 31 and are joined to the central flooring by angle members 32.

To further increase the sturdiness of the car the upright flanges 17 of the central flooring members 15 are connected to the upright webs of 35 the side flooring members 20 by Z-shaped members 33. These members definitely space the upright webs of the central and side floorings and resist lading and operating strains.

Each of the axle hoods 19 consists of a bail-shaped member 34 having a top horizontal web 35 with end extensions 36 which overlap the inwardly extending flanges 14 of the sills and are preferably welded thereto. Downwardly extending webs 37 of the axle hoods have outwardly turned flanges 38 which overlap the ends of the horizontal central floor sections 18 and are secured thereto as by rivets 40 thereby connecting said floor sections. These axle hoods also have outwardly turned flanges 41 extending vertically 45 and attached to the upright webs 17 of the central floor portions 15. The construction described provides a complete and continuous central floor portion supported primarily by the longitudinal sills but recessed transversely for the 55

accommodation of axles as will appear presently more in detail.

Wheel hoods 50, preferably of sheet metal, are arranged between each of the sill members 10 and 11 and its corresponding side wall 24. Each of the hoods has a substantially curved body portion 51 with corresponding outwardly turned flange 52 and inwardly turned flange 53. The flange 52 abuts the side wall of the car and is riveted thereto. Flange 53 abuts a filler 53' which is interposed between said flange and the sill 10 or 11, as the case may be, and is secured to the filler and to the sill by the rivets 21'. The wheel hoods 50 also have out-turned flanges 54 at the bottom which overlap the horizontal floor portions 23 at their ends adjacent the axle and are riveted in overlapping relation. This construction employs the wheel hoods as substantial means to assist in carrying the side walls and side floor sheets and presents continuous side flooring from end to end of the car, there being, however, indentations from the bottom upward to accommodate the wheels at the ends of the axles.

The structure as thus far described is composed of sheet metal and commercially rolled shapes and forms a mine car so constructed and reinforced as to be capable of resisting all of the ordinary strains of lading and operation. In completing the assembly cast axle seats or pedestals 55 are secured to the sills 10 and 11, respectively, the attachment being preferably to the bottom face of the inwardly extending flanges 14 of the sills by means of rivets 56. These pedestals are in the transverse plane of the axle hoods 19 and have flanges 57 registering opposite the outwardly turned flanges of the axle hoods and joined thereto by rivets 58 which pass through the flanges of the pedestals, the flanges 17 of central floor portions 15 and the overlapping flanges of the axle hoods 19 whereby the load is transmitted to the pedestals and thence to the axles of the car.

The axle receiving means or pedestals are preferably characterized by an inverted U-shaped opening 60 whereby an axle 61 may be introduced to and associated with the car body by a straight transverse relative movement as distinguished from an axial or longitudinal insertion of the axle. When the axles are so associated they are located in position in seats 62 of the pedestals and held against dislocation by pins 63 passed through the lower portion of the pedestals and removably secured therein by cotter pins 64. Each of the axles is equipped at either end with wheels 65 which may be mounted with antifriction bearings 66 or in any other suitable way to rotate on the axles.

It is to be noted that the pedestals are arranged preferably below the longitudinal sills and no weakness of the sills is effected in the present construction by reason of the cutting of slots or apertures for the reception of the axles. When the body and wheeled axles are assembled the plane of the axle is below the sills yet substantially higher than the central and side flooring. This, without weakening the body frame construction, lowers the center of gravity of the load with respect to the track upon which the car runs. It also provides a car of high lading capacity yet with side walls lowered so that the tops thereof are easily accessible from the ground. The body is given highly increased sturdiness by reason of the curved wheel hoods and the angular axle hoods and the means of locating and attaching same with respect to the sills, the floor-

ing and the side walls. Also the Z angle ties 33 serve with the axle hoods and wheel hoods to strengthen the body to resist the lading and operating strains without materially increasing the weight.

The car is further provided with end bumpers 10 and 11. These are substantially alike except for minor details of construction and only one will be described. The end wall 28 is terminated at 72 slightly above the flooring portions 15 and 23 10 allowing for the introduction of a lower horizontal flange 73 of a Z-shaped end sill 74 having an upright web 15 and an upper horizontally extending flange 16. This flange is centrally reinforced by a plate 17 and this reinforced portion 15 is apertured to receive a coupling pin 18. A wood bumper filler 79 has its rear face abutting the front face of the vertical web 15. The bumper has upper and lower metal clamping plates 80 and 81, respectively, the upper plate having an upturned flange 82 which abuts the web 15 of the end sill and is connected thereto by rivets which pass through the flange 82, web 15 and the end wall 28. The lower plate 81 has an extended flange 82' which laps the flooring and is secured thereto and to the flange 73 at 83. The assembly of bumper filler 79 and upper and lower plates is embraced for a portion of its width by a channel-shaped end member 84 which is secured in position by bolts 85 passing through the horizontal extensions of the member 84 and through the clamping plates and the bumper filler. This assembly is also recessed at 85' to receive the coupling pin 18.

Obviously this bumper construction has an effect toward increasing the rigidity and sturdiness of the car but it will be seen that the bumper construction does not necessarily enter into the invention in many of its broader aspects as the car is complete and rigidly self-sustaining in assembly with its axles irrespective of the bumper construction just previously described.

Commercial embodiments of a preferred form of the invention present the plane of the wall-tops approximately two feet from the track rails and the plane of the side floorings less than four inches from the track rails. It is obvious that in case of need the axles with their supporting wheels can be removed by jacking up the car body and removing the pins 63. The removal 50 may be effected without disturbing the roller bearing adjustment and assembly of wheels and axles. In original construction the axles are dropped into the pedestals 55 of the car when the latter is in bottom up position.

What is claimed is:

1. In a mine car, a body having side and end walls and side sills, axles arranged in a plane wholly below the side sills, a flooring located below the sills and axles and extending outwardly beyond the plane of the ends of the axles, and housings over the axles secured to the flooring.

2. In a mine car, longitudinal sills, pedestals secured to and depending from said sills, central and side flooring supported by the sills and arranged in a horizontal plane below the latter, axles arranged in the pedestals and positioned above the general plane of the flooring and wholly below the side sills, said side flooring extending transversely of the car beyond the plane of the ends of the axles, and means in the lower portions of the pedestals for retaining the axles against displacement.

3. In a mine car, a plurality of axles, longitudinal side sills arranged in a horizontal plane 75

- wholly above the axles, side walls spaced outwardly from the side sills, axle pedestals secured below the sills, and flooring suspended from the sills; the pedestals having open lower portions and the flooring having axle hoods in transverse alignment with the pedestals and connected thereto and forming therewith a plurality of channels for the reception of the said axles in a plane above the flooring.
4. In a mine car, longitudinal sills, side walls spaced outwardly from the sills, end walls connecting the side walls, central flooring suspended from the sills, axle pedestals secured to the sills, side flooring depending from the sills and extending to the side walls in substantially the plane of the central flooring, said side and central flooring being apertured to receive wheeled axles, and a plurality of wheeled axles arranged in the pedestals and positioned above the general plane of the side and central flooring and below the sills.
5. In a mine car, a plurality of axles having wheels, a body having side and end walls and a flooring joined with said walls, axle hoods and wheel hoods on the flooring, side sills, axle pedestals secured to the side sills and having their lower portions apertured to receive the axles in a plane above the general plane of the flooring and wholly below the side sills.
6. In a mine car, a plurality of axles having wheels, a body comprising spaced parallel longitudinal sills, sheet metal side walls spaced outwardly from and extending higher and lower than the horizontal plane of said sills, flooring between said sills and outwardly of the sills extending to the lower extremities of the walls, hoods associated with the flooring adapted to receive the axles and wheels; the plane of the axle axis being higher than the plane of the said wall extremities and lower than the plane of said sills.
7. In a mine car, longitudinal spaced parallel bulb angle sills, side walls outwardly spaced from and parallel with said sills, end walls connecting with said side walls and said sills, open-lower-end axle pedestals attached to said sills, wheel equipped axles located in the pedestals, and flooring portions between the sills and between the sills and the walls arranged in a general plane below the axle.
8. In a mine car, longitudinal spaced parallel bulb angle sills, side walls outwardly spaced from and parallel with said sills, end walls connecting with said side walls and sills, open-lower-end axle pedestals attached to horizontal flanges of said sills, wheel equipped axles located in the pedestals, flooring portions between the sills and between the sills and the walls arranged in a general plane below the axle, wheel hoods joining portions of said flooring, and axle hoods joining portions of said flooring.
9. In a mine car, longitudinal spaced parallel bulb angle sills, side walls outwardly spaced from and parallel with said sills, end walls connecting with said side walls and said sills, open-lower-end axle pedestals adapted to support said sills, wheel equipped axles located in the pedestals, flooring portions between the sills and between the sills and the walls arranged in a general plane below the axle, and wheel hoods set between the sills and side walls and secured thereto and to the flooring.
10. In a mine car, substantially vertical side and end walls of sheet metal, a pair of longitudinal sills between the walls and substantially higher than the plane of the lower extremities thereof, central flooring connecting the sills, side flooring connecting the sills and the lower extremities of the walls, and axle receiving means adapted to support said sills having seats in a plane higher than that of the central and side flooring.
11. In a mine car, substantially vertical side and end walls of sheet metal, a pair of longitudinal sills between the walls and substantially higher than the lower extremities thereof, central flooring connecting the sills, side flooring connecting the sills and the lower extremities of the walls, axle receiving means supporting said sills having seats in a plane higher than the central and side flooring, wheel hoods on the side flooring, and axle hoods on the central flooring.
12. A mine car comprising spaced parallel bulb angle sills having inwardly extending lower flanges, central flooring secured to and extending in a plane below said sills, axle hoods on said flooring, side flooring secured to and extending outwardly in a plane below said sills, side walls having lower extremities joining with the side flooring, and wheel hoods on said side flooring between the sills and the side walls; said wheel hoods having points of attachment to the sills, the side walls and the side flooring.
13. A mine car comprising spaced parallel longitudinal sills, side and end walls extending higher and lower than the plane of said sills, central and side flooring portions hung from the sills, and axle receiving members; the flooring and axle receiving members being recessed upwardly to receive and seat axles substantially above the general plane of the central and side flooring and substantially below the sills.
14. A mine car, spaced parallel longitudinal sills, side and end walls extending higher and lower than the plane of said sills, central and side flooring portions hung from the sills, axle receiving members; the flooring and axle receiving members being open to receive and seat axles substantially above the general plane of the central and side flooring and substantially below the sills, wheel hoods attached to the side flooring between the sill and the side walls, and axle hoods depending from the sills and attached to the central flooring.
15. In a mine car, a pair of spaced parallel longitudinal bulb angle sills, axle receiving members secured to said sills and extending therebelow, axles in said members, central floor portions secured to said sills and extending horizontally below the plane of the axles, side walls spaced outwardly from said sills, end walls joining said side walls, and side floor portions connecting said sills with the lower extremities of said side walls and extending horizontally lower than the plane of the axles and beyond the ends thereof.
16. In a mine car, a pair of spaced parallel longitudinal bulb angle sills, axle receiving members secured to said sills and extending therebelow, axles in said members, central floor portions secured to said sills and extending horizontally lower than the plane of the axles, side walls spaced outwardly from said sills, end walls joining said side walls, side floor portions connecting said sills with the lower extremities of said side walls and extending horizontally lower than the plane of the axles and beyond the ends thereof, and wheel hoods in the space between and attached to the side walls and adjacent sills.
17. In a mine car, a pair of spaced longitudinal

sills, a channel shaped member connecting said sills providing a central flooring, side flooring having flanges secured to said sills, and axle pedestals in the space between the central and side flooring members and secured to the under side of the sills, said pedestals having axle bearing portions arranged in a plane above the side flooring.

18. In a mine car, a pair of spaced longitudinal sills, a channel shaped member connecting said sills providing a central flooring, side flooring arranged in substantially the same plane as the central flooring and provided with upwardly extending flanges secured to said sills, and axle pedestals in the space between the central and side flooring members and secured to the under side of the sills; said pedestals having open lower portions for the reception of an axle.

19. In a mine car, a lading holding body including a central lading supporting bottom and wheel recessed side floor portions, longitudinally extending body stiffeners projecting into the lading zone of the car and arranged in a plane spaced a substantial distance above but connected with the central lading bottom and side floor portions, and axles below the body stiffeners by which said body is supported.

20. In a mine car, a lading holding body including a central lading supporting bottom and wheel recessed side floor portions, axles arranged in a plane spaced a substantial distance above the central lading bottom and side floor portions, and longitudinally extending body stiffeners wholly above the axles, said stiffeners projecting into the lading zone of the car and being spaced above but connected with the central lading bottom and side floor portions.

21. In a mine car, a body comprising side and end walls and sill members extending from end wall to end wall, a central lading bottom suspended from said sill members, and side floor portions extending from the sill members to the side walls and suspended from said sill members,

the effective lading supporting portions of said central lading bottom and side floor portions being spaced a substantial distance below the sill members.

22. In a mine car, a body comprising side and end walls and sill members extending from end wall to end wall, axles by which the body is supported, a central lading bottom suspended below said sill members and arranged in a plane below the axles, and side floor portions extending from the sill members to the side walls and being suspended in a plane spaced below said sill members.

23. In a mine car, a car body comprising a floor arranged in substantially a uniform horizontal plane from side to side and end and side walls extending upwardly from the floor, a pair of sill members extending from end to end of the car body in inwardly spaced relation to the side walls and in upwardly spaced relation to the bottom, and vertically extending stiffener members secured to the end walls and to said sill members.

24. In a mine car, a plurality of axles, longitudinal side sills arranged in a horizontal plane wholly above the axles, side walls spaced outwardly from the side sills, axle pedestals secured to the lower portions of said sills and depending from the latter, and flooring suspended from the sills and connected with the pedestals, the pedestals having open lower portions and the flooring having axle hoods in transverse alignment with the pedestals and connected thereto and forming therewith a plurality of channels spaced respectively longitudinally of the car adapted to receive said axles in a plane above the flooring.

25. In a mine car, side sills and a lading bottom therebetween formed of a plurality of spaced units substantially straight from end to end and having angle-shaped flanges along their side edge portions connected to and resting on the sills, and axle housings between adjacent units connected thereto and to the side sills.

HENRY P. FIELD.
